PAINT ROLLER TRAY

Donald W. Layman, 3355 S. Ash St., Denver, Colo.

Filed Oct. 14, 1965, Ser. No. 87,485

Term of patent 14 years

(Cl. D9—2)

FIG. 1.

FIG. 2.

FIG. 3.

FIGURE 1 is a top plan view of the paint roller tray, showing my new design;

FIGURE 2 is a sectional view taken along lines 2—2 of FIGURE 1; and,

FIGURE 3 is a frontal isometric view thereof.

The broken line showings in FIGURE 3 are for illustrative purposes only.

I claim:

The ornamental design for a paint roller tray, as shown and described.
